Inventor,

E. L. Freeman

United States Patent Office.

E. L. FREEMAN, OF WILLIAMSTOWN, NEW YORK.

Letters Patent No. 89,137, dated April 20, 1869.

IMPROVEMENT IN CULTIVATOR-TOOTH

The Schedule referred to in these Letters Patent and making part of the same

To all whom it may concern:

Be it known that I, E. L. FREEMAN, of Williams-
town, in the county of Oswego, and State of New York,
have made new and useful Improvements in Devices for
Preparing Land for Sowing, and for Cultivating Crops;
and I do hereby declare that the following is a full and
complete description of the construction and operation
of the same, reference being had to the accompanying
drawings, making part of this specification.

This invention consists in the peculiar form of a cul-
tivator-tooth,

A representing the shank, and

B, the head that locks over the beam, and is held in
place by a key, driven into the hole on the back or
front side of the shank.

From the lower end of the shank A, the tooth curves
slightly backward and downward, being widened and
flattened, as shown at C.

From this point it bends forward, gradually con-
tracting in width, until it reaches the point D, where
it presents a nearly horizontal position.

From D to the edge of the point, the vertical thick-
ness diminishes, terminating in a vertical cutting-edge,
E, which should be made of steel, and tempered.

In this structure I have a substantial and durable
tooth, adapted to the purpose of culture, or of prepar-
ing the ground for the seed.

What I claim as my improvement, and desire to se-
cure by Letters Patent, is—

The harrow or cultivator-tooth herein described,
when constructed as set forth.

E. L. FREEMAN.
